UNITED STATES PATENT OFFICE.

LUELLA CORNELL, OF TOLEDO, OHIO.

UNCOUPLING DEVICE.

1,298,669.

Specification of Letters Patent.

Patented Apr. 1, 1919.

Application filed January 13, 1919. Serial No. 270,937.

To all whom it may concern:

Be it known that I, LUELLA CORNELL, a citizen of the United States, and a resident of Toledo, in the county of Lucas and State of Ohio, have invented certain new and useful Uncoupling Devices; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to an uncoupling device and it has for its object to provide a means for operating a coupling pin at points remote therefrom, that is, at points that are safe for the trainmen to operate from. It 20 also has for its object to provide an efficient uncoupling device which may be applied to and used in connection with the car couplers now commonly used by the railroads.

The invention may be modified by those 25 skilled in the art without departing from the spirit thereof. I have selected a construction containing the invention for purposes of illustration and shall describe the same hereinafter. The construction selected 30 is illustrated in the accompanying drawings.

The figure illustrates a view of a box car having the uncoupling device attached thereto.

In the figure, 1 is a box car, it being understood, however, that the uncoupling device may be attached to and used in connection with any form of a railroad car, such as a coal car or a gondola car. 2 is the draw-bar attached to the car in a manner well known in the art and having a link socket 3 in which the coupling pin 4 is located and mounted for vertical movements through the draw-bar 2 and through the link socket 3.

The pin may be operated either from the 45 top of the car or from the side corner of the car. It is connected by means of a short chain 5 with an angular rod 6. The body portion of the rod 6 extends vertically upward and its upper end is located near the 50 top of the car. The upper end 7 may be bent into the form of a handle whereby the rod 6 may be seized and lifted upward which will operate also to lift the pin 4 and permit the coupling link to enter the socket 3 55 of the draw-bar 2. This obviates the necessity of the brakemen, or trainmen, climb-

ing down the end of the car in order that the car may be coupled to another car.

In order to prevent the rotation of the rod and also to keep the pin in alignment with the hole in the draw-bar, guide rods 8 are provided, which are suitably located at a point slightly remote from the end of the car and on each side of the laterally extending portion 9 of the rod 6. As the rod 6 is moved up and down, the portion 9 of the rod slides between the rods 8 and thus keeps the pin in alignment with the hole in the draw-bar. The rods 8 may be bent at their ends to form bracket portions whereby they 70 may be secured to the end of car. Their length is such that they will extend over the whole distance that the laterally extending portion 9 of the rod 6 may be moved. The movements of the rod 6 are limited by the 75 guide members 10, through which the rod 6 extends, and adjustable collars 11 that are secured to the rods 6. The adjustable collars 11 are located between the guide members 10 and so located, with reference to the 80 guide members 10, that when the pin 4 is in its coupling position, the lower parts 10 and 11 will be in contact and when the pin 4 is clear of the socket 3 although its lower end may still be in the hold of the draw-bar 2, 85 the upper parts 10 and 11 will be in contact. Moreover, this distance or movement of the pin 4 and the rod 6 is less than the vertical measurements of the rods 8, 8.

If desired, the running board 12 located 90 on the top of the car, may be extended over the end of the car and be provided with an opening 13 through which the hand of the brakeman may be inserted in order that the handle may be seized and lifted to uncouple 95 the car.

In order that the car may be uncoupled from the side of the car, or rather from the corner of the car without stepping over the tracks, a rod 14 may be connected with the 100 laterally extending portion 9 of the rod 6 and on the outside of the rods 8, that is, between the rods 8 and the end of the laterally extending portion 9 of the rod 6. The rod 14 is loosely held in the eye 15 formed in the 105 bracket 16, that is secured to the end of the car. The rod 14 may be secured in position against extended longitudinal movement by means of adjustable collars 17 so located on opposite sides of the brackets 16 110 as to permit such longitudinal movements as are necessary to allow vertical movements of

the rod 6. The rod 14 may also be provided with a handle 18.

When it is desired to operate the coupling pin 4 from the corner of the car the lever 5 which is thus formed of the rod 14 pivoting in the eye 15 may be operated so as to cause the rod 6 to be lifted and consequently to lift the pin 4. The movements of the rod 14 and consequently the pin 4 will be limited 10 by the relation of the collars 11 and the guide members 10.

I claim:

In an uncoupling device, a draw bar, a coupling pin located in the draw bar, an 15 angular rod supported on the end of the car the body portion of the rod extending

vertically along the end of the car and the laterally extending portion of the rod extending over a coupling pin, means connecting the coupling pin with the laterally extending portion of the rod, guide members located on each side of the laterally extending portion of the rod and at a point remote from the end of the car, the rod having adjustable collars for limiting the movements 20 of the rod and the pin relative to the draw bar and so located as to prevent the withdrawal of the lower end of the pin out of the draw bar.

In testimony whereof, I have hereunto 25 signed my name to this specification.

LUELLA CORNELL.
